CLAIM

The ornamental design for a breathing tube assembly, as
shown and described.

DESCRIPTION

The patent or application file contains at least one drawing
executed in color. Copies of this patent or patent application
publication with color drawing(s) will be provided by the
Office upon request and payment of the necessary fee.

FIG. 1 is a front, left side and top perspective view of a first
embodiment of a breathing tube assembly showing our new
design.

FIG. 2 is a rear, right side and bottom perspective view
showing a bottom surface thereof.

FIG. 3 is a right side view thereof.

FIG. 4 is a left side view thereof.

FIG. 5 is a rear view thereof.

FIG. 6 is a front view thereof.

FIG. 7 is a top view thereof.

FIG. 8 is a bottom view thereof.

FIG. 9 is a front, left side and top perspective view of a
second embodiment of a breathing tube assembly showing
our new design.

FIG. 10 is a rear, right side and bottom perspective view
showing a bottom surface thereof.

FIG. 11 is a right side view thereof.

FIG. 12 is a left side view thereof.

FIG. 13 is a rear view thereof.

FIG. 14 is a front view thereof.

FIG. 15 is a top view thereof; and,

FIG. 16 is a bottom view thereof.

In FIGS. 1–8, the tube portion is blue in color, as shown. In
FIGS. 9–16, the tube portion is shown in dark gray and the
first and second connectors are shown in light gray to solely
illustrate a contrast in color between the tube portion and one
or both of the connectors.

The breathing tube assembly is shown with a symbolic break
in the length of the tube. The appearance of any portion of
the article between the break lines forms no part of the

(Continued)

claimed design. The broken lines in the drawings depict portions of the breathing tube assembly that form no part of the claimed design.
